UNITED STATES PATENT OFFICE.

HENRY MARTIN, OF LOUISVILLE, KENTUCKY.

FOLDING LIFE-BOAT.

Specification of Letters Patent No. 23,595, dated April 12, 1859.

To all whom it may concern:

Be it known that I, HENRY MARTIN, of Louisville, in the county of Jefferson and State of Kentucky, have invented a new and Improved Folding Boat; and I do hereby declare that the following is a full, clear, and exact description of the same, reference being had to the accompanying drawings, making part of this specification, in which—
5 Figure 1, represents a longitudinal vertical section of my invention, the line x, x , Fig. 3, indicating the plane of section. Fig. 2, is a transverse vertical section of do, the plane of section being indicated by the line 10 y, y , Fig. 3, and Fig. 3, is a plan or top view of do.

Similar letters of reference in the three figures indicate corresponding parts of my boat.

20 This invention consists in hinging to the upper surface of the keel the bottom boards to which the seats are attached by hinges, and to its (the keels) sides the ribs in such a manner that one half of the same folds 25 toward one side and the other half toward the other side and that the same when turned up, support the gunwale bars which are hinged to the stern and to the bow of the boat, and that they (the ribs) keep a 30 water proof cover, which is attached to the gunwale bars and to the keel, in an expanded state together with air chambers, which are arranged one in the bow and the other in the stern of the vessel and which are 35 attached to two of the ribs by means of eyes or loops and which when released from these ribs fold up in the manner of bellows the whole being so arranged that the seats together with the bottom boards fold up, and 40 that the ribs can be turned down one half toward one side and the other half toward the other and that the gunwale bars can be folded down so as to lie flat against the keel, so that the boat, when those are folded 45 up, takes up little room and that the same, when expanded serves as a life-boat by reason of the two air chambers and at the same time it offers comfortable sitting room by means of the seats which are attached 50 to the bottom boards.

To enable those skilled in the art to fully understand use and construct my invention I will proceed to describe it.

A, is the keel which is turned up at both 55 ends so as to form the bow B, and the stern

C, of the boat. Attached to the top of the keel and covering the central part of the same are the bottom boards D, by means of a rod a , which is rigidly attached to the keel and which passes through a series of hinges 60 b , which are fastened to the bottom boards.

E, are the seats which when in a horizontal position, are supported by folding legs c , and which are hinged to the bottom boards by means of rods d , which pass through 65 loops e , at the ends of the seats and through hinges e' , which are secured to the lower surface of the bottom boards D, as clearly represented in Fig. 2. Each of the seats consists of two parts, and the two parts 70 when in a horizontal position, are united by a dove-tailed projection d' , which is attached to one of the parts and which fits in a corresponding recess d'' , in the other part, so that both the parts are supported by the 75 same leg c , which is secured to one of the parts of each seat.

The bottom boards, when unfolded, rest against the ribs F, which are secured to the sides of the keel by means of hinges f , in 80 such a manner, that one half of the same folds toward one and the other half toward the other side, one on the top of the other and close up to the keel, and the bottom boards are provided with slots e^* , which fit 85 over the several ribs so that the latter, when the bottom boards are unfolded, are prevented from moving laterally. These ribs serve to support the gunwale-bars G, which are hinged to the bow B, and to the stern 90 C, and a water-proof cover H, which is secured to the outside of the gunwale-bars and to the under side of the keel is kept expanded by the ribs, when the same are turned out so as to support the gunwale- 95 bars. The two middle ones of the ribs are cut out so as to form projections f' , (see Fig. 2) which fit under short bars f'' , which are rigidly attached to the under side of the gunwale bars, and by these means the position 100 of the gunwale bars is strengthened against any pressure which has a tendency to expand the same in the middle.

I, I, are two air chambers which are attached one to the stern and one to the bow 105 of the boat in such a manner that they fold up like a pair of bellows, and hinged to the outer edges of these chambers are the eyes or loops i , which fit over pins j , attached to two of the ribs F, so that by hooking these 110

loops over the pins the air chambers are kept in an expanded state, but if unhooked they can be collapsed. In order to fold the boat the seats are first turned up and the 5 bottom-boards are folded together so as to come in a vertical position, the air chambers are unhooked from the ribs to which they are attached by means of the loops *i*, and the ribs are turned down so as to lie flat 10 against the keel, one half of them toward one and the other half toward the other side as above described, and the gunwale-bars are turned down so as to lie close up to the keel, and by this operation the air chambers 15 are compressed and the whole boat can be stowed away without taking up much room. At the same time it is very easy and it takes but a few minutes time to fix the boat up ready for use.

20 I do not claim of themselves either the

hinged or pivoted ribs or the hinged gunwale-bars; but

What I do claim as new and desire to secure by Letters Patent, is,

The within described arrangement of the 25 ribs, one half of which fold toward one and the other half toward the other side in combination with the hinged bottom boards *D*, which by means of slots *e**, secure the ribs in an upright position and which are provided 30 with seats *E*, which are hinged to the bottom boards by means of rods *d*; and which are connected by the dove-tailed projections *d*',—the whole being constructed and operated substantially as and for the purpose 35 set forth.

HENRY MARTIN.
